GEORGE C. COOK, OF MILLINGTON, NEW JERSEY

UNDERFEED STOKER APPARATUS

Application filed April 1, 1927. Serial No. 180,168.

The invention relates to underfeed stokers of the inclined multiple retort type, and more particularly to the fuel bed controlling means thereof. In stokers of the aforesaid type, there is a tendency when burning coking coals of high carbon content for a solid dense mass of unbroken coke to be formed in the retorts which mass is practically impenetrable by the air supplied through the tuyères associated with the retorts. As this coke mass is forced out of the retort it tends to retain its previous shape and thus will not cover the nose of the respective intermediate tuyères, causing holes to burn through the fuel bed over said noses and leaving thin lanes practically throughout the length of the bed. This results in lack of uniformity in fuel bed conditions, low rate of combustion per square foot of grate surface as well as a large percentage of excess air; and this is especially marked when preheated air is utilized in the combustion of the fuel and with thin fuel beds.

The invention has for its object to obviate this burning through of the fuel bed and the formation of a mass of unbroken coke by providing means for breaking up said mass in the various retorts, thereby avoiding the formation of holes in said bed and affording uniformity of the same through the free penetration by and uniform distribution of the air supplied, resulting in greater rates of and more complete combustion.

The nature of the invention, however, will best be understood when described in connection with the accompanying drawings, in which—

Fig. 1 is a fragmentary longitudinal sectional view through a furnace provided with an underfeed stoker of the inclined multiple retort type.

Fig. 2 is a fragmentary transverse sectional view on an enlarged scale, taken on the line 2—2, Fig. 1, and looking in the direction of the arrows.

Fig. 3 is a transverse, fragmentary horizontal sectional view on an enlarged scale, taken on the line 3—3, Fig. 1, and looking in the direction of the arrows.

Fig. 4 illustrates a modification, being a de-

tail longitudinal section through a pusher plate with rocker arm thereof and link attached thereto.

Fig. 5 is an enlarged elevation of a pusher member and portion of the plate to which it is hinged, the full line position indicating its lowered condition for a predetermined setting, while the dotted line position indicates the relative position of the pusher member at the limit of its elevated condition.

Referring to the drawings, the invention is shown applied to a standard type furnace comprising the front wall 10 and bridge wall 11 with ash pit 12, the stoker being of the inclined multiple retort underfeed type suitable for large installations in which a series of inclined retorts 13 are disposed transversely of the furnace with intermediate tuyères 14. The latter are in connection with the wind box 15 to which air, which may be preheated, is supplied through an air duct 16. Fuel is fed from hoppers 17 to primary or main rams 18 which are reciprocated by suitable mechanism (not shown) from a drive shaft 19 and in manner well understood to deliver the fuel into the respective retorts 13.

Over the bottom 20 of the various retorts is designed to reciprocate a plurality of members which may serve also as sets of secondary or pusher rams 21 to advance the fuel through the respective retorts; and in accordance with the invention, these members are designed to have in addition to the reciprocatory motion an oscillating motion in a vertical plane, the latter motion being provided for the purpose of breaking up the coal in a retort and effecting thereby a more efficient combustion of the same. Secondary rams have heretofore been utilized for advancing the fuel through a retort and have been actuated from the movement of the primary ram; and in carrying out the present invention, the said secondary rams may be similarly actuated from the primary ram 18.

The said members or secondary rams 21, however, are arranged to be hingedly connected to a sliding member as, for example, a plate 22 which is designed to reciprocate over the retort bottom 20 and cover a longitudinal opening 23 provided therein to admit of the

passage downwardly through said bottom of a bearing arm 24 which is fixedly secured to said plate as an integral part thereof. Said opening accommodates also the oscillatory movement of a secondary ram member, the bottom edge of which extends normally below not only the surface of its surrounding carrying plate but also beneath the bottom 20 of the retort, it being noted that the said plate will assist, also, in advancing the fuel.

10 The reciprocatory motion for the secondary rams is, as hereinbefore stated, to be derived from the movement of the primary ram 18, for example, through a drive arm 25 extending downwardly therefrom and arranged to be adjustably connected to a drive rod 26 which is mounted for reciprocation in the furnace wall 27. A lost motion device, comprising a pin 28 adapted to be fitted in various openings 29 at the forked end of the rod 26 and into which fits the arm 25, provides means for varying the extent of reciprocation of the drive rod 26 and, correspondingly, the extent of reciprocation of the secondary rams. 15 A further lost motion device 30, similar to the aforesaid device, is provided at the opposite end of drive rod 26, or at various points along same when more than two sets of secondary rams are utilized, so that the extent 20 of reciprocation of a succeeding secondary ram may be made less than that of the preceding ram.

25 The secondary ram 21 may be of various forms and, as indicated in Figs. 1, 2 and 5 of the drawings, consists of a flat-top, box-like member of triangular cross section with arcuate front wall.

30 In order to effect this oscillation of the secondary ram relatively to its carrying plate 22, which latter is designed to be reciprocated along the bottom 20 of a retort as hereinbefore set forth, provision is made to suitably connect the same with the reciprocating drive rod 26. To this end, a secondary ram 35 is provided with a downwardly extending arm 40 which may be integral therewith, as shown in Figs. 1, 2 and 5, and is connected by means of a link 41 with the one end of a lever 42 pivoted intermediate its ends to the arm 24 extending downwardly from plate 22. The opposite or lower end of said lever 42 is pivotally attached to the drive rod 26 and thus imparts the motion of said rod to the arm 40 to effect a consequent oscillation of 40 said secondary ram member 21 in accordance with the reciprocation of rod 26. This oscillation is limited by a lost motion connection on the link 41 as through a pin or stop 43 designed to engage one side of the arm 24 and a stop 44 carried by the link 41 at the opposite side of said arm, the link being provided with a number of openings 45 for receiving the said stop members which are thus adjustable along said link to provide for lost motion. As the 45 rod 26 is moved toward the rear of the fur-

nace, it first causes the lever 42 to rotate the secondary ram 21 downwardly until the pin or stop 43 engages arm 24 when said lever is held to the arm, and the plate 22 will then be moved to the rear of the furnace. When the 70 rod 26 is moved in the opposite direction, the ram is raised until the other pin 44 engages with the arm 24 as the lever 42 is again moved and the plate 22 moves then in the opposite direction or backwardly. The extent of oscillation of a secondary ram is adjustable and fixed by the positioning of the stops 43 and 44 on the link 41.

75 I have found it desirable, also, to duplicate the secondary rams for each set, as indicated in Fig. 1, which is accomplished by means of a connecting link member 46 extending downwardly below the retort bottom 20 from the one ram and connecting the same with the other.

80 Furthermore, in order to seal the contacts between the front and side walls of a secondary ram member and the surrounding portions of the plate which carries the same, there is provided a spring-steel lining sheet 85 50, Fig. 4, which is preferably corrugated horizontally as shown and secured over the corresponding plate edges along the front and sides of the opening 23 as by means of rivets 51. This will provide an effective closure and seal against sifting of the coal into the wind-box but will still allow the oscillation of a secondary ram relatively to the plate and eliminate binding.

90 95 I claim:

1. In an underfeed stoker of the inclined multiple retort type: the combination with elements reciprocable and oscillatable in the respective retorts, and means to reciprocate the same; of means to elevate simultaneously all the reciprocable and oscillatable elements of a retort and also to depress simultaneously all of said elements.

105 110 115 2. In an underfeed stoker of the inclined multiple retort type: the combination with elements reciprocable and oscillatable in the respective retorts, and means to reciprocate the same; of means to maintain elevated a said reciprocable and oscillatable element substantially during its stroke up its inclined retort.

120 125 130 3. In an underfeed stoker of the inclined multiple retort type: the combination with elements reciprocable and oscillatable in the respective retorts, and means to reciprocate the same; of means to maintain depressed a said reciprocable and oscillatable element substantially during its stroke down its inclined retort.

4. In an underfeed stoker of the inclined multiple retort type: the combination with elements reciprocable and oscillatable in the respective retorts, and means to reciprocate the same; of means to elevate in its retort a reciprocable and oscillatable element at the

beginning of its stroke up its inclined retort and to maintain the same elevated therein substantially to the end of its said stroke.

5. In an underfeed stoker of the inclined multiple retort type including a reciprocable primary ram for introducing fuel to the furnace, and means to reciprocate said ram: secondary rams, a member slidable over a retort bottom and to which a secondary ram is pivotally attached, said member having an arm extending downwardly through a slot in the retort bottom, an arm rigidly attached to said secondary ram, a lever fulcrumed to the arm of the slidable member, a link secured to one end of the lever and to the arm of said secondary ram, and reciprocating mechanism pivotally connected to the opposite end of said lever for reciprocating the slidable member and attached secondary ram.

6. In an underfeed stoker of the inclined multiple retort type including a reciprocable primary ram for introducing fuel to the furnace, and means to reciprocate said ram: secondary rams, a member slidable over a retort bottom and to which a secondary ram is pivotally attached, said member having an arm extending downwardly through a slot in the retort bottom, an arm rigidly attached to said secondary ram, a lever fulcrumed to the arm of the slidable member, a link secured to one end of the lever and to the arm of said secondary ram and connected with the slidable member arm, and reciprocating mechanism pivotally connected to the opposite end of said lever for reciprocating the slidable member and attached secondary ram.

7. In an underfeed stoker of the inclined multiple retort type including a reciprocable primary ram for introducing fuel to the furnace, and means to reciprocate said ram: secondary rams, a member slidable over a retort bottom and to which a secondary ram is pivotally attached, said member having an arm extending downwardly through a slot in the retort bottom, an arm rigidly attached to said secondary ram, a lever fulcrumed to the arm of the slidable member, a link adjustably secured to one end of the lever and to the arm of said secondary ram, and reciprocating mechanism pivotally connected to the opposite end of said lever for reciprocating the slidable member and attached secondary ram.

8. In an underfeed stoker of the inclined multiple retort type including a reciprocable primary ram for introducing fuel to the furnace, and means to reciprocate said ram: secondary rams comprising hollow box-like members of triangular shape open underneath, a plate slidable over a retort bottom and to which a secondary ram is pivotally attached, said plate having an arm extending downwardly through a slot in the retort bot-

tom, an arm rigidly attached to said secondary ram, a lever fulcrumed to the arm of the plate, a link adjustably connecting the two said arms and connected to one end of said lever, and reciprocating mechanism pivotally connected to the other end of said lever for reciprocating the slidable plate and attached secondary ram.

9. In an underfeed stoker of the inclined multiple retort type including a reciprocable primary ram for introducing fuel to the furnace, and means to reciprocate said ram: secondary rams comprising hollow box-like members of triangular shape open underneath, a plate slidable over a retort bottom and to which a secondary ram is pivotally attached, said plate having an arm extending downwardly through a slot in the retort bottom, an arm rigidly attached to said secondary ram, a lever fulcrumed to the arm of the plate, a link adjustably connecting the two said arms and connected to one end of said lever, and reciprocating mechanism pivotally and adjustably connected to the other end of said lever for reciprocating the slidable plate and attached secondary ram.

10. In an underfeed stoker of the inclined multiple retort type including a reciprocable primary ram for introducing fuel to the furnace, and means to reciprocate said ram: a plurality of members reciprocable with said ram and oscillatable in the retorts, and means to impart to succeeding members reciprocations of different extent.

11. In an underfeed stoker of the inclined multiple retort type: the combination with elements reciprocable and oscillatable in the respective retorts, and means to reciprocate the same; of means to maintain elevated a said reciprocable and oscillatable element substantially during its stroke up its inclined retort, and means to adjust the extent of oscillation of an element.

12. In an underfeed stoker of the inclined multiple retort type including a reciprocable primary ram for introducing fuel to the furnace, and means to reciprocate said ram: a plate slidable over a retort bottom and provided with an opening, a member hingedly secured to the plate to oscillate through said opening, and means to seal the said oscillatable member with respect to the opening.

13. In an underfeed stoker of the inclined multiple retort type including a reciprocable primary ram for introducing fuel to the furnace, and means to reciprocate said ram: a plate slidable over a retort bottom and provided with a rectangular opening, a member hinged to the plate at one side of the opening to oscillate therethrough, and a flexible lining member secured to the plate over the remaining three sides of the opening to seal said oscillatable member with respect thereto.

14. In an underfeed stoker of the inclined multiple retort type including a reciprocable

primary ram for introducing fuel to the furnace, and means to reciprocate said ram: a plate slideable over a retort bottom and provided with a rectangular opening, a member hinged to the plate at one side of the opening to oscillate therethrough, a flexible lining member secured to the plate over the remaining three sides of the opening to seal said oscillatable member with respect thereto, said plate having an arm extending downwardly through a slot in the retort bottom, an arm rigidly attached to the member hingedly secured to the plate, a lever fulcrumed to the arm of the plate, a link secured to one end of the lever and to the arm of the hingedly secured member, and reciprocating mechanism pivotally connected to the other end of the lever.

15. In an inclined stoker-retort: a reciprocable rousing member therein, and means to reciprocate said member and to elevate it at the beginning of its stroke up its retort and to maintain it in the elevated position substantially to the end of the stroke, said means being adapted also to depress the rousing member and to maintain it in the depressed position substantially to the end of its stroke down the retort.

In testimony whereof I affix my signature.
